(57) **CLAIM**

The ornamental design for a wide-brim hat hanger, as shown and described.

DESCRIPTION

FIG. 1 is a perspective view of a wide-brim hat hanger, showing my new design in an extended configuration; FIG. 2 is a front elevational view thereof; FIG. 3 is a rear elevational view thereof; FIG. 4 is a left-side elevational view thereof; FIG. 5 is a right-side elevational view thereof; FIG. 6 is a top plan view thereof; FIG. 7 is a bottom plan view thereof; and, FIG. 8 is a perspective view thereof, illustrated in a partially collapsed configuration.

The broken lines in FIG. 1 depicting a hat show environmental matter that forms no part of the claimed design. The remaining broken lines depict stitching, and do form part of the claimed design.
